UNITED STATES PATENT OFFICE.

GEORGE B. THOMAS, OF BRIDGEPORT, CONNECTICUT, ASSIGNOR TO THE BEYANT ELECTRIC COMPANY, OF BRIDGEPORT, CONNECTICUT, A CORPORATION OF CONNECTICUT.

CURRENT-TAP.

1,249,856.

Specification of Letters Patent. Patented Dec. 11, 1917.

Application filed January 15, 1916. Serial No. 72,325.

To all whom it may concern:

Be it known that I, GEORGE B. THOMAS, a citizen of the United States of America, and residing at Bridgeport, in the county 5 of Fairfield and State of Connecticut, have invented a certain new and Improved Current-Tap, of which the following is a specification.

My invention relates to current taps and 10 particularly to a tap device associated with an electric lamp socket or the like to permit a branch circuit to be tapped off from the wire terminals of the latter. The object of my invention is to provide a simple, inexpensive and convenient construction whereby 15 this result may be attained in a socket whether or not the latter has a switch for controlling the lamp circuit.

In the accompanying drawings,

20 Figure 1 is a vertical section through a switchless socket in which my invention is embodied in one form;

Fig. 2 is a vertical section at right angles thereto;

25 Fig. 3 is a horizontal section on the line 3—3, Fig. 1;

Fig. 4 is a vertical section on the line 4—4, Fig. 6 through a switch socket in which my invention is embodied;

30 Fig. 5 is a section at right angles thereto on the line 5—5, Fig. 6;

Fig. 6 is a horizontal section on the line 6—6, Fig. 4;

35 Fig. 7 is a plan of the body of a pull socket in which my invention is embodied; and

Fig. 8 is a horizontal section therethrough on a line corresponding to line 6—6, Fig. 4.

The present invention relates to a tap of 40 the detachable type in which the connection is made through an attachment plug, the jacks on which coöperate with terminals carried by the socket. In the simplest form of construction, viz., that shown in Figs. 45 1 to 3, the invention is embodied in a switchless socket comprising the usual cap and shell 10 and 11 with insulating lining 12 and screw nipple 13 for securing the socket to a suitable fixture. Within the casing is 50 mounted an insulating body comprising a pair of buttons 14 and 15 united by the two bolts 16 and 17 which pierce the buttons and take into tapped holes in the yoke 18 which overlies the base flange of the shell 55 contact 19 for the lamp. The outer button

15 carries the two wire terminals 20 and 21, the former of which is connected to the shell 19 by a screw 22 taking into the base of the binding screw terminal. The center contact 23 is connected in usual manner by the screw 60 24 to the base of the wire terminal 21.

The two buttons 14 and 15 have registering lateral extensions 25 and 26 which are recessed on their meeting faces to afford channels 27 and 28 within which lie the tap 65 terminals 29 and 30. These terminals are preferably of spring sheet metal with offset bases riveted to the flanges 31 and 32 offset from the bases of the wire terminals. Inasmuch as the channels 27 and 28 pierce the 70 boss formed by these lateral extensions of the buttons, they afford guideways for the entering jacks 33 and 34 of a coöperating attachment plug 35 of common construction. The size of the channels and the arrangement of the terminals 29 and 30 therein is 75 preferably such that the bent ends of the latter bear against the sides of the channels which form the guideways for the jacks of the attachment plug, so that the jacks as 80 they enter press the terminals away from the sides of the channel with a brushing action, thus insuring a good contact therewith.

The casing 11 and its lining 12 are cut away at 36 to permit the boss to project 85 therethrough, as illustrated.

In Figs. 4, 5 and 6 the adaptation of the invention to a socket of common type having a key operated switch is shown. The construction of the switch may be of any 90 suitable type and that shown is merely an example comprising a common mechanism such as shown in the Perkins Patent 629,927. The wire terminals 37 and 38 are arranged substantially as in the construction heretofore explained, with the difference however that they now form standards by which the two buttons 39 and 40 are connected together. The shell contact 41 is directly connected to the terminal 38 by the screw 42. 100 The terminal 37 has confined between its end and the button 39 a spring switch contact 43 which projects therefrom over the switch block 44 through which the circuit is established to the center contact 45 in 105 well understood manner. The tap terminals 46 and 47 are fastened at their bases to flanges 48 and 49 at the end of offset extensions of the bases of the wire terminals 37 and 38. It is desirable to locate the boss, 110

within which the tap terminals 46 and 47 lie, at a point substantially opposite the key 50 for operating the switch, since by this arrangement the latching devices commonly employed in standard casings of this type are not disturbed.

In the construction shown in Figs. 7 and 8 the application of the invention to a pull socket is illustrated. In this construction a single pole-double break switch of the well known ratchet type is shown. The two buttons 51 and 52 are spaced apart by three standards 53, 54 and 55, the first of which carries the usual chain bell 56, while the two latter carry two binding screws 57 and 58 and form the wire terminals of the socket. The terminal 54 is directly connected through the screw 59 with the shell terminal 41 which is thus constantly connected in one branch of the circuit. The other terminal 55 has secured beneath the same one of the switch terminals 61 which is angled over one of the teeth of the ratchet boss formed on the inner face of the button 52. The opposite tooth of the ratchet boss is overlaid by the terminal 62 which is connected to the center contact of the socket in well understood manner. The two tap terminals 63 and 64 are not symmetrically arranged in this construction as in the others, but their bases are attached to the wire terminals in like manner and their contacts are presented within the channels of the laterally extending boss in precisely the same manner as in the other constructions.

In all of the constructions illustrated the tap terminals extend so far into the boss 26 that the point at which the jacks of the plug 35 make and break contact therewith is located outside the area of the shell. This is a feature of particular importance in switched sockets in view of the possible danger of arcing which might occur were the break to occur within the casing in proximity to the switch elements.

Various adaptations of the invention to other socket arrangements will readily suggest themselves to those skilled in the art and I do not limit my invention to lamp

sockets or to the details shown which may be modified without departing from what I claim as my invention.

I claim as my invention:

1. An electric lamp socket comprising a metallic casing with lateral aperture, an insulating body within the casing and having a pierced boss projecting through said lateral aperture, lamp and wire terminals carried by said insulating body, and tap terminals electrically connected to said wire terminals and projecting into said pierced boss beyond the area of the casing to receive the terminals of a coöperating attachment plug and make and break contact therewith outside the area of the casing.

2. An electric lamp socket comprising a metallic casing with lateral aperture, an insulating body within the casing comprising a pair of buttons having registering slotted projections which form a pierced boss passing through said lateral aperture in the casing, lamp and wire terminals carried by said insulating body, and tap terminals electrically and inseparably connected to said wire terminals and projecting into said pierced boss beyond the area of the casing to receive the terminals of a coöperating attachment plug.

3. An electric lamp socket comprising a metallic casing with lateral aperture, an insulating body within the casing comprising a pair of insulating buttons having registering slotted projections which form a boss pierced by a pair of parallel guide-ways and projecting through said lateral aperture in the casing, lamp and wire terminals carried by said insulating body, and tap terminals electrically connected to said wire terminals and projecting into the respective guideways in said boss to receive the terminals of a co-operating attachment plug.

In testimony whereof I have signed my name to this specification, in the presence of two subscribing witnesses.

GEORGE B. THOMAS.
